WINDOW VENTILATOR

Albert Di Loreto, Erie, Pa.

Application February 26, 1954, Serial No. 29,233

Term of patent 14 years

(Cl. D62—4)

FIG. 1

FIG. 2

To all whom it may concern:

Be it known that I, Albert Di Loreto, a citizen of the United States, residing at Erie, in the county of Erie and State of Pennsylvania, have invented a new, original, and ornamental Design for a Window Ventilator, of which the following is a specification, reference being had to the accompanying drawing, forming part thereof.

In the drawing:

Fig. 1 is a front view of the window ventilator showing my new design; and

Fig. 2 is a side view of my ventilator.

I claim:

The ornamental design for a window ventilator, as shown.
